DENTAL SPATULA

William B. Dragan, R.F.D. Burr St.,
Fairfield, Conn. 06430

Original design application Apr. 5, 1971, Ser. No.
131,566. Divided and this application Oct. 17,
1972, Ser. No. 300,446

Term of patent 14 years

Int. Cl. D24—02

U.S. Cl. D24—1 D

FIG. 2

FIG. 1

FIG. 3

FIG. 4

FIG. 5

FIG. 1 is a top plan view of a dental spatula showing my new design, the opposite side being a mirror image thereof.

FIG. 2 is a left end view thereof.

FIG. 3 is a right end view thereof.

FIG. 4 is a side elevation view thereof.

FIG. 5 is a perspective view thereof.

This is a divisional application of application Ser. No. D. 131,566 filed Apr. 5, 1971 entitled Dental Spoon and Spatula Set.

I claim:

The ornamental design for a dental spatula, substantially as shown and described.
